UNITED STATES PATENT OFFICE.

JOHN W. BAILEY, OF JERSEY CITY, NEW JERSEY, ASSIGNOR, BY MESNE ASSIGNMENTS, TO UNITED LEAD COMPANY, A CORPORATION OF NEW JERSEY.

APPARATUS FOR PRODUCING WHITE LEAD.

No. 830,196.

Specification of Letters Patent.

Patented Sept. 4, 1906.

Application filed December 5, 1900. Serial No. 38,757.

To all whom it may concern:

Be it known that I, JOHN W. BAILEY, a citizen of the United States, and a resident of Jersey City, in the county of Hudson, State of New Jersey, have invented an Improved Apparatus for Producing Lead Carbonate, or White Lead, of which the following is a full, clear, and exact specification, reference being had to the accompanying drawings, which form a part hereof.

The invention relates to an improved apparatus for manufacturing lead carbonate, or what is known as "white lead," or any similar product; and the object of the invention is to provide means for handling finely divided or comminuted metallic lead while it is passing through the various stages of treatment needed to convert it into lead carbonate or commercial white lead, except that after being passed through said apparatus the white lead must of course be washed and dried.

One object of the invention is to enable the white lead to be produced automatically and continuously and economically and at the same time to furnish a product which is superior in quality to that which is made by old and well-known processes.

To that end my invention consists, first, in the combination in such apparatus of a corrodng-chamber of any suitable shape and size, a support for the finely divided or comminuted lead in said chamber—such, for example, as a floor or shelf to carry the lead—and stirrers adapted to stir or turn the lead over, so as to expose it thoroughly to the action of the corrodng-gas and at the same time to move or throw the lead forward through the said chamber, and means of any suitable kind to support and carry or move the stirrers. In the best form of my invention I employ a series of stirrers so arranged as to coöperate with one another in stirring or turning over the comminuted lead very thoroughly, so as to expose every particle of the same to the action of the corrodng-gas. In the best form of my invention also I employ suitable means for supplying the corrodng-gas to said chamber.

My invention also consists in the employment of a suitable carrying-chain to which the stirrers are attached for carrying the stirrers and means for supporting and moving the chain.

My invention also consists in employing two or more rows of stirrers arranged longitudinally of the corrodng-chamber and so placed with reference to one another as to stir and move every part of the comminuted lead.

My invention also consists in combining with some or all of the features already mentioned a plurality of stirrers having the form of plows, the said plows being consecutively arranged with relation to their path of movement in the chamber and being adapted to turn the lead over and at the same time slowly feed it forward, and the plows preferably being placed alternately in reversed positions, whereby one plow turns the lead over in one direction and the succeeding plow turns the same mass of lead over in the opposite direction, and thus the lead is thoroughly stirred and very completely exposed to the action of the corrodng-gas and is at the same time gradually moved forward through the corrodng-chamber, the advancing movement of the lead being at a rate slower than the movement of the plows.

My invention also consists in the combination with the other necessary parts of an endless chain adapted to move through the corrodng-chamber and provided with a series of cross-rods and a row of plows pivoted to each cross-rod and means for supporting and moving the endless chain. In the best form of this part of the invention the plows of each row are placed in a reversed position relatively to the plows of the receding row.

My invention also consists in the combination in such an apparatus of a corrodng-chamber, a series of overlapping shelves placed one above another, forming a zigzag channel through the chamber, and means for stirring the lead and at the same time moving it over the said shelves and causing it to drop from shelf to shelf until it reaches the point of discharge.

My invention also consists in the combination in such an apparatus of a corrodng-chamber and a series of overlapping shelves placed one above another, forming a zigzag channel through the corrodng-chamber, and a series of stirrers adapted to stir the lead and at the same time move it forward on said shelves and cause it to drop from shelf to shelf, and means for supporting and moving the stirrers over the shelves. In the best

form of my invention I arrange the stirrers or plows in the manner already described and attach them to an endless chain adapted to carry the stirrers or plows through the corrodng-chamber and over the shelves in a zigzag course, whereby the lead is thoroughly stirred and exposed to the corrodng-gas and is at the same time moved or fed over the shelves successively until it reaches the point of discharge.

My invention also consists in devices for automatically feeding the finely-divided or comminuted lead into the corrodng-chamber and for moistening or sprinkling the same automatically and for supplying the corrodng-gas to the said chamber.

My invention also consists of certain other features of construction and combinations of parts hereinafter described and claimed.

My improved apparatus is shown in the accompanying drawings, in which—

Figure 1 is a vertical longitudinal section of the apparatus. Fig. 2 is a vertical cross-section of the same, taken on the line $x-x$ of Fig. 1. Fig. 3 is a detail view of the device for feeding the lead into the chamber, and Fig. 4 is a detail view showing the construction of the endless chain for carrying the plows and also of the sprinkling or moistening apparatus.

Similar numbers indicate similar parts in the different figures.

Referring to the drawings, 11 are the walls of the corrodng-chamber. This corrodng-chamber is made of any suitable dimensions and in any suitable manner. This chamber is provided with a series of shelves or floors which overlap one another in the manner shown in Fig. 1. These shelves operate to support the lead after it has been fed into the chamber and while it is being exposed to the action of the corrodng-gas. In the form shown in Fig. 1 the uppermost shelf extends to and is partly supported by the front wall of the chamber. In the other direction it extends to a point some little distance away from the rear wall of the chamber, thereby leaving a space in which are placed the sprocket-wheels 33, which support and move the endless chain. This shelf is provided with an opening or slot 4 near its rear end, through which the lead drops from the top shelf to the shelf below. This shelf is also provided with a trap-door 5 or other suitable device or opening to permit the passage of the endless chain in the manner illustrated. The other shelves or floors are similarly constructed, except that the second shelf from the top extends to the rear wall of the chamber instead of to the front wall, thereby leaving a space for the passage of the chain at the front end of the chamber instead of at the rear. The shelves, which are connected with the rear or discharge end wall of the chamber, are not provided with trap-doors at that

end, as the chain does not have to pass through them at that point.

66 are stirrers which in the form of my invention which is shown in the drawings are made in the shape of plows, the construction of which is more fully set out in Figs. 3 and 4. The stirrers or plows are attached to and carried by an endless chain 7. This chain can be constructed in any suitable manner and can be supported and operated by any suitable means. In the form shown in the drawings the endless chain consists of cross-rods 8, to which the plows are pivoted. These cross-rods are connected together at their ends by links 99 of any suitable construction. (See Fig. 4.)

The cross-rods 8 are provided at their ends with the friction-wheels 1010, which run upon tracks or ways 1111, fastened in any suitable way to the side walls of the corrodng-chamber. In this way the chain is kept at the proper distance above the shelves 22 as it is moved through the corrodng-chamber, as a result of which the plows 66 are made to penetrate entirely through the mass of lead resting upon the shelves and to thoroughly stir the lead. Each cross-rod is provided with a row of plows—as shown, for example, in Fig. 2, where nine plows are attached to each rod. The cross-rods are put at any suitable distance from one another, and the plows attached to one rod are preferably arranged immediately behind the plows attached to the preceding rod, whereby the plows are consecutively arranged with relation to their path of movement in the corrodng-chamber. The plows or blades of the plows of each longitudinal row thus formed are placed alternately in reversed positions, as illustrated in Fig. 2—that is to say, the blade of one plow is made to project to the left and the blade of the succeeding plow in the same longitudinal row is made to project to the right, as a result of which the plows in passing through the lead carried by the shelves turn it over, first in one direction and then in the opposite direction. By reason of the fact that the plows are pivoted to the cross-rods the plows always hang suspended from the chain no matter which side of the chain be uppermost. The direction of travel of the chain is clearly indicated in Fig. 1. The chain and its plows first pass over the top shelf and then around the uppermost sprocket-wheels at the left end, as indicated in the drawings, then over the second shelf, then around the sprocket-wheels opposite the second shelf on the right-hand side of Fig. 1, and so on back and forth over each one of the shelves until it reaches the lowest part of the corrodng-chamber, when the chain passes over the sprocket-wheel 12 and then up through the trap-doors 5, over the sprocket-wheel 13, and then continuously around the same circuit. 14 is a hopper,

which is supplied from time to time with finely divided or comminuted lead. From the hopper 14 the lead falls into the pockets 15 of a feed-drum 16. This drum is supported within and revolves within the shell 17. The shell 17 is provided with an aperture at the top and at the bottom. The lead from the hopper 14 passes through the upper aperture of the shell into the pockets of the drum and falls through the lower aperture of the shell onto the uppermost shelf 2 in the corroding-chamber.

The drum 16 is provided at its ends with the projecting arms 18. Each cross-rod of 15 the endless chain is provided with projecting arms 19, adapted to strike against the arms 18 of the drum, so as to cause the drum to make a quarter-revolution as each rod of the chain passes underneath it. The result of 20 this is that a pocketful of lead is dropped upon the top shelf as each cross-rod passes underneath the drum and immediately in front of the row of plows carried by the next cross-rod. 20 is a moistening device for supplying a limited amount of a suitable solution of acetic acid and water to the lead immediately after it is fed into the chamber. This moistening device consists of a tube 21, provided with suitable openings or perforations 22. The tube 21 is supplied with moistening liquid through a supply-pipe 23, which is provided with any suitable form of valve, as shown. 24 is an arm connected with this valve, by means of which the valve 25 may be opened or closed, so as to admit a charge of moistening liquid to the tube. The arms 19 of the cross-rods are adapted to strike against the arm 24 when the cross-rods pass underneath the moistening device and 30 to thereby open the valve in the supply-pipe 23, and thus cause a regulated quantity of the moistening liquid to be sprinkled upon the lead. When the arm 19 has moved forward so as to disengage the arm 24, that arm 40 is drawn back into its normal position by the spring 26, so as to close the valve in the supply-pipe 23 and cut off the supply of moistening liquid.

By adjusting the arm 24 and the connected valve the amount of moistening liquid that is sprinkled upon the lead each time the valve is opened can be regulated or adjusted. It is also apparent that if it be deemed desirable to moisten the lead in the corroding-chamber at several different points more than one moistening device can be employed—that is to say, a moistening device similar to one just described can be inserted at any place in the corroding-chamber, and any 55 number of these moistening devices can be used.

27 is a pipe placed at the discharge end of the corroding-chamber and suitably perforated, through which the carbonic-acid gas,

together with air, steam, and acetic-acid vapor, is supplied to the corroding-chamber.

28 is a vessel into which the corroded lead falls through the openings 4 in the lowest shelf. This vessel is removed from time to time and the carbonate of lead is washed and 70 dried by any well-known means.

29 29 are flues or pipes for the escape of the corroding-gas.

The operation of my improved apparatus is as follows: The finely-commiinuted lead, 75 which may be made by any of the usual methods, is fed into the hopper 14, from which it is fed automatically in regulated quantities on to the uppermost shelf of the corroding-chamber by means of the drum 16. 80 The lead is turned over and gradually worked forward by the stirrers or plows 6 6, and as each row of plows passes underneath the moistening device 20 a regulated quantity of moistening liquid is sprinkled upon 85 the lead immediately beneath. This spray is generally made of a mixture of acetic acid and water, preferably of about eight per cent. acid to ninety-two per cent. water. The lead is then in condition to be acted upon by 90 the corroding-gas. The plows continue to stir or turn over the lead, and thus expose it thoroughly to the action of the corroding-gas and at the same time feed it forward until the lead reaches the discharge end of the 95 uppermost shelf, when it drops through the opening 4 on to the shelf below. It is then acted upon in like manner by the plows and carried forward on the second shelf until it reaches the end of the same and drops 100 through the opening 4 on to the third shelf, and so on until the lead finally drops into the receptacle 28, at which time it has been very thoroughly subjected to the corroding-gas and very completely corroded. When the 105 apparatus is started, a supply of carbonic-acid gas, air, moisture, and acetic-acid vapor, warmed to a temperature of about 120° Farenheit, is forced in through the perforated pipe 27, which in the best form of my 110 invention is located below the lowest shelf. By reason of the construction of these shelves the gases are forced to travel between the shelves in close proximity to the stock under treatment as it is being stirred 115 and thrown first one way and then another by the plows. The gases are thus forced to pass over each shelf and very near to the same until they reach the top of the chamber, when they escape through the waste flues or 120 pipes 29.

Many advantages result from the use of my improved apparatus. The corrosion of the lead is much more rapid than in the methods heretofore employed, one reason being that 125 the corroding-gases are brought into closer contact with the stock under treatment. The white lead made in this apparatus is

substantially free from dust or other impurities. There is no tendency on the part of the corroded lead to form into lumps, as in former processes. In this apparatus the 5 lead is very thoroughly stirred, and thus exposed to the action of the corroding-gas, and yet the disturbances are periodical—that is to say, the lead is not in constant motion—and this fact also leads to a more thorough 10 corrosion of the lead. In this apparatus also the granulation of the lead in the process of manufacture is substantially prevented. The whole operation is automatic, including the loading or charging of the lead, the stirring, and the unloading. This makes the 15 process much less dangerous to life and health.

In processes heretofore employed the operatives were exposed more or less to the 20 poisonous gases and dust, which made these former processes dangerous to health and life. My apparatus overcomes this serious defect.

What I claim as new, and desire to secure 25 by Letters Patent, is—

1. In apparatus for making white lead or similar products, the combination of a corroding-chamber, a support for comminuted lead in said chamber, means for supplying 30 comminuted lead to said support, a series of stirrers adapted to stir the lead and to advance it over the said support at a rate materially slower than the movement of the stirrers, and means for supplying a corroding-gas to said chamber, substantially as set forth.

2. In apparatus for making white lead or similar products, the combination of a corroding-chamber, a support for comminuted lead in said chamber, means for supplying comminuted lead to said support, a series of stirrers adapted to stir the lead and to advance it with relation to the said support at a rate materially slower than the movement of 45 the stirrers, a chain to which the stirrers are attached, means for supporting and moving the chain, and means for supplying a corroding-gas to said chamber, substantially as set forth.

3. In an apparatus for making white lead or similar products, the combination of a corroding-chamber, a support for comminuted lead in the said chamber, means for supplying comminuted lead to said support, a plurality 55 of stirrers consecutively arranged with relation to their path of movement in the corroding-chamber and adapted to stir the lead and to advance it with relation to said support at a rate materially slower than the movement 60 of the stirrers, means for supporting and moving said stirrers, and means for supplying corroding-gas to said chamber, substantially as set forth.

4. In apparatus for making white lead or 65 similar products, the combination of a cor-

roding-chamber, a support for the lead in said chamber, a plurality of stirrers consecutively arranged with relation to their movement in the corroding-chamber and adapted to stir the lead and to advance it through the said 70 chamber at a rate slower than the movement of the stirrers, an endless chain to which the stirrers are attached, means for supporting and moving the chain, and means for supplying a corroding-gas to said chamber, substantially 75 as set forth.

5. In apparatus for making white lead or similar products, the combination of a corroding-chamber, a support for the lead in said chamber, a plurality of plows consecutively 80 arranged with relation to their path of movement in the corroding-chamber and adapted to turn the lead over and feed it forward, the plows being placed alternately in reversed positions, means for supporting and moving the 85 plows and means for supplying a corroding-gas to said chamber, substantially as set forth.

6. In apparatus for making white lead or similar products, the combination of a corroding-chamber, a support for the lead in the 90 said chamber, a plurality of rows of plows consecutively arranged with relation to their path of movement in the corroding-chamber and adapted to turn the lead over and feed it forward, the rows of plows being placed 95 alternately in reversed positions, means for supporting and moving the plows, and means for supplying a corroding-gas to said chamber, substantially as set forth.

7. In apparatus for making white lead or similar products, the combination of a corroding-chamber, a support for the lead in said chamber, means for supplying comminuted lead to said support, an endless chain adapted to move through said chamber, provided with a series of cross-rods, a row of plows pivoted to each cross-rod, said plows being constructed to advance the lead at a rate materially slower than the movement of the chain, means for supporting and moving the chain, and means for supplying a corroding-gas to said chamber, substantially as set forth.

8. In apparatus for making white lead or similar products, the combination of a corroding-chamber, a support for the lead in said chamber, an endless chain, adapted to move through said chamber, provided with a series of cross-rods, a row of plows pivoted to each cross-rod, the plows of each row being placed in a reversed position relatively to the plows 110 of the preceding row, means for supporting and moving the chain, and means for supplying a corroding-gas to said chamber, substantially as set forth.

9. In apparatus for making white lead or similar products, the combination of a corroding-chamber, a series of overlapping shelves placed one above another, means for supplying comminuted lead to the uppermost shelf, means for stirring the lead and ad-

vancing it over said shelves at a rate materially slower than the movement of the stirring means and causing it to drop from shelf to shelf, and means for supplying corroding-gas to said chamber, substantially as set forth.

10. In apparatus for making white lead or similar products, the combination of a corroding-chamber, a series of overlapping shelves placed one above another, a chain adapted to move over said shelves successively, a series of stirrers attached to said chain and adapted to stir the lead and move it forward on said shelves at a rate slower than the movements of the stirrers, and cause it to drop from shelf to shelf and means for supporting and moving the chain, and means for supplying corroding-gas to said chamber, substantially as set forth.

20. 11. In apparatus for making white lead or similar products, the combination of a corroding-chamber, a series of overlapping shelves placed one above another, a chain adapted to move over said shelves successively, a plurality of plows consecutively arranged with relation to their path of movement in the corroding-chamber and adapted to turn the lead over and feed it forward on the said shelves and cause it to drop from shelf to shelf the plows being attached to said chain and placed alternately in reversed positions, means for supporting and moving the chain, and means for supplying a corroding-gas to said chamber, substantially as set forth.

35. 12. In apparatus for making white lead or similar products, the combination of a corroding-chamber, a series of overlapping shelves placed one above another, a chain adapted to move over said shelves successively, one or more rows of plows consecutively arranged with relation to their path of movement in the corroding-chamber and adapted to turn the lead over and feed it forward on the said shelves and cause it to drop from shelf to shelf, the rows of plows being attached to said chain, and placed alternately in reversed positions, means for supporting and moving the chain, and means for supplying a corroding-gas to said chamber, substantially as set forth.

45. 13. In apparatus for making white lead or similar products, the combination of a corroding-chamber, a series of overlapping floors or shelves placed one above another, an endless chain adapted to move over said floors or shelves successively, the chain being provided with a series of cross-rods, a row of plows pivoted to each cross-rod, means for supporting and moving the chain and means for supplying a corroding-gas to said chamber, substantially as set forth.

55. 14. In apparatus for making white lead or similar products, the combination of a corroding-chamber, a series of overlapping

shelves placed one above another, an endless chain adapted to move over said shelves successively, the chain being provided with a series of cross-rods, a row of plows pivoted to each cross-rod, the plows of each row being placed in a reversed position relatively to the plows of the preceding row, means for supporting and moving the chain and means for supplying a corroding-gas to said chamber, substantially as set forth.

60. 15. In apparatus for making white lead or similar products, the combination of a corroding-chamber, a support for the lead in said chamber, a series of stirrers adapted to stir the lead and to advance it through the said chamber at a rate slower than the movement of the stirrers, a chain to which the stirrers are attached, means for supporting and moving the chain, means for feeding comminuted lead into said chamber automatically, and means for supplying the corroding-gas to said chamber, substantially as set forth.

70. 16. In apparatus for making white lead or similar products, the combination of a corroding-chamber, a support for the lead in said chamber, a series of stirrers adapted to stir the lead and to slowly advance it through the said chamber, a chain to which the stirrers are attached, means for supporting and moving the chain, means for feeding comminuted lead into said chamber automatically, automatic means for supplying a limited amount of moisture to the lead in said chamber, and means for supplying the corroding-gas to said chamber, substantially as set forth.

75. 17. In apparatus for making white lead and similar products, the combination of a corroding-chamber, a support for the lead in said chamber, a plurality of stirrers consecutively arranged with relation to their path of movement in the corroding-chamber and adapted to stir the lead and move it through the said chamber at a rate slower than the movement of the stirrers, an endless chain to which the stirrers are attached, means for supporting and moving the chain, means for automatically feeding the lead into said chamber, said means being operated by an endless chain, and means for supplying a corroding-gas to said chamber, substantially as set forth.

80. 18. In apparatus for making white lead or similar products, the combination of a corroding-chamber, a support for the lead in said chamber, a plurality of stirrers consecutively arranged with relation to their path of movement in the corroding-chamber, and adapted to stir the lead and move it through the said chamber, an endless chain to which the stirrers are attached, means for supporting and moving the chain, automatic means for supplying a limited amount of moisture

- to the lead in said chamber, said means being operated by the endless chain, and means for supplying a corroding-gas to said chamber, substantially as set forth.
- 5 19. In an apparatus for making white lead or similar products, the combination of a corroding-chamber, a series of supports for the comminuted lead placed one above another in said chamber, an endless carrier adapted to move over said shelves successively, a series of stirrers attached to said carrier and adapted to stir the lead and move it in opposite directions on said shelves, said stirrers having inclined surfaces facing in opposite

directions whereby each stirrer is adapted to 15 stir the lead while moving in opposite directions, means for supporting and moving said carrier, and means for supplying corroding-gas to said chamber, substantially as set forth.

20 In testimony whereof I have signed my name to this specification in the presence of two subscribing witnesses.

JOHN W. BAILEY.
